UNITED STATES PATENT OFFICE.

ROMEO M. NASTASIA, OF LONG BRANCH, NEW JERSEY, ASSIGNOR OF ONE-FIFTH TO
JOHN NASTASIA, OF LONG BRANCH, NEW JERSEY.

MANTLE.

Application filed October 31, 1925. Serial No. 66,967.

This invention relates to mantles of the combustible type, and has especial reference to the type of mantle used in an apparatus for the treatment of the ear such as the one disclosed in the United States Letters Patent No. 1,554,876 granted to me.

One of the principal objects of the present invention is the production of a mantle capable of being used in an apparatus for the treatment of the ear which mantle when ignited and consumed produces gases heavier than air which will descend into the ear and produce beneficial results to the ear.

Another object of the invention is to provide means for facilitating the ignition of the mantle characterized hereinbefore.

Another object of the invention is to provide a mantle of the character mentioned with means for taking up the heavy gaseous particles or impurities in the generated gas as it descends to thus obtain a clarified gas before the gas enters the ear.

Another object of the invention is to combine with a mantle of the character mentioned a holder which supports the mantle, the mantle being treated with a chemical to render a portion thereof non-combustible, or noxious to fire, so that the mantle will not burn all the way down to one of the holder parts, and yet not interfere with the proper combustion and descension of the gases.

The nature of the invention and the distinguishing features and advantages will appear when the following specification is read in conjunction with the accompanying drawing, in which—

Figure 1 is a side elevation of the mantle of the present invention, its holder and a portion of an apparatus for the treatment of the ear, the latter being shown in section.

Fig. 2 is a vertical sectional view taken substantially on the line 2—2 of Fig. 1 of the mantle and its holder alone.

Fig. 3 is a perspective view of the outer mantle element.

Fig. 4 is a perspective view of the inner mantle element.

Referring now more particularly to the several views of the drawing it will be apparent that, there is shown a mantle 10 supported by a holder 11 which is capable of being used in an apparatus for the treatment of the ear, a portion of which is designated at 12. A comprehensive showing and description of the nature and advantages of

the apparatus in which the mantle of the present invention is used appears in the Letters Patent hereinbefore referred to. The mantle 10, in the present instance, is made of two elements, an element 13 and an element 14. The element 13 is made up of a piece of white, preferably woven, fabric of single ply and is formed into the shape of a truncated cone. The element 13 has good capillary and absorptive properties and is capable of being consumed when ignited. The fabric from which the element 13 is made is saturated with a chemical which produces heavy gases when ignited. In the present instance the fabric is saturated with a hydrocarbon of the Marsh gas series having the formula C_nH_{2n+2} . The chemical is applied to a portion of the fabric from the brim so as to occur from the brim down substantially two and one-half inches, the portion being indicated at 15, and the remaining portion 16 is treated with a suitable chemical which renders the same non-combustible, and renders the same safe and closes the pores so as not to permit air to enter at the bottom of the mantle or to interfere with the combustion and descension of the gases generated. The element 14 is made preferably of a single ply of fabric, and also formed into the shape of a truncated cone slightly smaller than the element 13 so as to fit closely within the same. The fabric from which the element 14 is made is of wider mesh so that the strands thereof will be far enough apart to provide interstices, or a slight rough surface that will cover the entire inside of the mantle. The fabric from which the element 14 is made has good capillary and absorptive properties and is capable of being consumed when ignited.

The fabric from which the element 14 is made is not saturated but is utilized for taking up heavy carbon impurities which collect on the rough surface thereof to thus purify the gases as they descend permitting only a clarified gas to leave the discharge end or opening at the bottom of the mantle on its way to the ear.

In order to facilitate ignition of the mantle, each of the elements 13 and 14 is provided with a pair of tabs 17 which are integral with or may be attached in any suitable manner to the material from which the elements are made.

The holder 11 which supports the mantle

10 may be made in any preferred manner to permit the gases to descend, and in the present instance consists of a nipple 18 having screw threads 19, there being a frame 20 connected to the nipple 18. The frame 20 is made of wire and consists of diverging members 21 and ring members 22 arranged transversely of the members 21 and connected thereto. The frame 20 is arranged with 10 in the mantle 10, as shown most clearly in Fig. 2, and the lower end of the mantle extends into the nipple 18 and is attached thereto as at 23 in any preferred manner. The frame 20 prevents the mantle from lapsing as it is being consumed. The mantle is connected in the apparatus by virtue of the threaded end of the nipple 18 being screwed into a part of the apparatus, as shown in Fig. 1.

15 20 When it is desired to generate the gases, the tabs 17 are ignited and as a result the mantle will burn and be consumed, the gases generated being heavier than air and will descend into the ear. The mantle will be

consumed down to the portion 16, which, 25 as stated, is non-combustible, thus means is provided for permitting only the desired kind of gas to enter the ear being treated.

What I claim is—

1. A mantle for use in an apparatus for 30 the treatment of the ear, consisting of a combustible material saturated with a chemical which when ignited generates gases heavier than air and said material also being treated with a chemical to render a portion 35 thereof non-combustible.

2. A mantle for use in an apparatus for 40 the treatment of the ear, consisting of two plies of material, one of the plies being combustible and foraminous, and the other ply 45 being combustible and surrounding the former ply and saturated with a chemical which produces gases heavier than air, and the outer ply of material also being treated with a chemical to render a portion thereof non- combustible.

ROMEON M. NASTASIA.
